(57) **CLAIM**

The ornamental design for a computer chassis, as shown and described.

DESCRIPTION

FIG. 1 is a perspective view of a computer chassis, according to some embodiments of the claimed design;
FIG. 2 is a front view of the computer chassis thereof;
FIG. 3 is a rear view of the computer chassis thereof;
FIG. 4 is a left view of the computer chassis thereof;
FIG. 5 is a right view of the computer chassis thereof;
FIG. 6 is a top view of the computer chassis thereof; and,
FIG. 7 is a bottom view of the computer chassis thereof.
The broken lines in the drawings are included for the purpose of illustrating environmental structure and form no part of the claimed design.

1 Claim, 7 Drawing Sheets
